Emelio E. Tremarco, Newark, N. J., assignor to
Casco Products Corporation, Bridgeport, Conn.,
a corporation of Connecticut

Application January 21, 1949, Serial No. 350

Term of patent 7 years

(Cl. D58—12.6)

To all whom it may concern:

Be it known that I, Emelio E. Tremarco, a citizen of the United States, residing at Newark, county of Essex, and State of New Jersey, have invented a new, original, and ornamental Design for a Toolbox, of which the following is a specification, reference being had to the accompanying drawing, forming part hereof.

In the drawing:

Figure 1 is a front perspective view of a toolbox, showing my new design.

Fig. 2 is a side view of the same, the opposite side being the same.

Fig. 3 is a side view of the same with the top opened.

I claim:

The ornamental design for a toolbox, as shown and described.

EMELIO E. TREMARCO.
